CRUCIBLE SUPPORT

Raymond D. York, University, Va., assignor to
Raymond D. York, as trusteeOriginal application December 16, 1938, Serial No.
246,236. Divided and this application August
16, 1939, Serial No. 290,460

14 Claims. (Cl. 22—82)

This invention relates to crucible supports, and is a division of my copending application Serial No. 246,236, filed December 16, 1938.

In my copending application referred to I have disclosed a crucible support adapted for use particularly with heavy crucibles and provided with means for supporting the crucible for turning movement to a pouring position, together with means for connecting a handle to the tilting structure to facilitate the pouring of the metal, the handle having means for preventing accidental dislodgement thereof during the pouring operation.

An important object of the present invention is to provide novel latching means for supporting the crucible and the tilting structure associated therewith in its normal vertical position thus preventing accidental turning of the crucible until the operator is ready to pour metal therefrom.

A further object is to provide a crucible supporting unit carrying crucible tongs movable independently of the unit to grip a crucible and movable bodily with the unit to tilt the crucible to a pouring position, and to provide a novel latching device for holding the crucible, the gripping tongs and the supporting unit in fixed normal vertical position until it is desired to pour metal from the crucible.

A further object is to provide a supporting structure which rotatably carries the crucible supporting unit for tilting movement to facilitate pouring of the metal from the crucible, and to provide a single latch mechanism between the crucible supporting unit and the main supporting structure to positively prevent tilting movement of the crucible, tongs and supporting unit until the operator is ready to pour metal from the crucible.

A further object is to provide a crucible supporting unit, a pair of crucible engaging tong levers, and means for actuating said levers, all constructed and arranged with respect to each other to provide a single bodily movable unit which is tiltable to pour metal from the crucible, and to provide a single latch device operable for normally preventing tilting movement of the bodily movable structure.

Other objects and advantages of the invention will become apparent during the course of the following description.

In the drawings I have shown one embodiment of the invention. In this showing:

Figure 1 is a front elevation of the mechanism showing a crucible supported thereby.

Figure 2 is a sectional view taken on line 2—2 of Figure 1.

Figure 3 is a sectional view taken on line 3—3 of Figure 1.

Figure 4 is a sectional view taken on line 4—4 of Figure 1, parts being shown in elevation and parts being broken away.

Figure 5 is a sectional view taken on line 5—5 of Figure 1, and,

Figure 6 is a detail perspective view of one of the crucible-engaging jaw elements.

Referring to the drawings, the numeral 10 designates a crucible supported by an article supporting unit indicated as a whole by the numeral 11. This unit is rotatably carried by a supporting structure indicated as a whole by the numeral 12 for turning or tilting movement relative thereto in a manner to be described.

The supporting unit 11 comprises a vertical member 13 and oppositely projecting integral parallel horizontal members 14 rigidly formed on the lower end thereof. The ends of the horizontal members 14 are turned downwardly to provide depending pairs of spaced vertical members 16.

A pair of arms 18 are respectively pivoted to the pairs of vertical members 16 by bolts 20, each arm 18 lying between the members of the associated pair 16 for a purpose to be described. Crucible gripping members 21 are carried by the lower ends of the arms 18 and are movable into or out of engagement with the crucible 10 upon pivotal movement of the arms 18 about the pivot bolts 20. The members 21 are detachably connected to the arms 18 in a manner to be described.

A shaft 23 is provided to effect pivotal movement of the arms 18 and a consequent movement of the crucible gripping members 21 into or out of engagement with the crucible 10. The vertical member 13 of the supporting unit 11 provides a journal 24 for the shaft 23. Endwise movement of the shaft 23 relative to the vertical member 13 is prevented by collars 25 which are secured to the shaft 23 by pins 27, the collars 25 abutting vertical faces of the member 13. The respective ends 29 and 30 of the shaft 23 are threaded in opposite directions to provide conventional right hand threads on the end 29 and left hand threads on the end 30. The shaft 23 is preferably squared at both ends as at 31 in order that a wrench may be used at either end of the shaft to rotate it.

Trunnion cradles 33 are provided on the respective upper ends of the arms 18. Each of the

trunnion cradles 33 is provided with spaced pairs of vertical members 35 to receive trunnions 36. The trunnions are carried by sleeves 37 internally threaded for engagement with the threaded portions of the shaft 23. Bolts 40 extend through the members 35 transversely of the trunnions 36 to prevent disengagement thereof from the respective cradles 33 and 34.

By reason of the oppositely threaded ends 29 and 30 of the shaft 23 having engagement with the internally threaded sleeves 37, it will be apparent that rotation of the shaft 23 will cause pivotal movement of the members 18 about the bolts 20 in a manner which will effect simultaneous movement of the crucible gripping members 21 into or out of engagement with the crucible 10.

The gripping members 21 are frictionally engageable with the sides of the crucible 10 and have their gripping surfaces shaped to conform to the shape of the crucible. Each of the gripping members 21 is removably secured to the lower end of one of the members 18 in order that various sizes of the gripping members may be used according to the crucible to be supported thereby. Each of the gripping members 21 is provided with a pair of lugs 41 spaced from each other a distance approximately equal to the thickness of each of the members 18. Abutments 42 are formed on the lower ends of the members 18 and for the purpose of providing a key fit of the lugs 41 with the abutments 42, it will be noted that the contacting faces of these elements slope inwardly and upwardly as at 43 toward the article to be engaged. Openings 44 are formed in the members 18 to receive wedges 45 which are driven into engagement with the upper edges of the lugs 41 to securely hold the lower edges thereof in engagement with the abutments 42. The mechanism for detachably securing the gripping members to their supporting members is illustrated and described in my copending application Serial No. 232,005, filed September 27, 1938.

Means are preferably provided to properly position the members 21 with respect to the side of the crucible. To this end, an adjustable positioning plate 46 is provided which may be brought into contact with the top 47 of the crucible. Pairs of fingers 48 are formed on the plate 46 and are spaced to provide elongated slots 49. The fingers 48 are positioned and slidable between the members 14 in order that the plate 46 and the top of the crucible 47 will be properly positioned relative to the supporting unit 11 according to the size of the crucible to be supported. To secure the plate 46 to the arms 14, bolts 50 are provided which pass through the slots 49. The bolts 50 are provided with enlarged rectangular heads 51 which frictionally engage the fingers 48 as at 52. Openings are provided in one of the arms 14 corresponding to the shape of the heads 51 to prevent turning movement of the bolts 50 relative to the members 14. Nuts 53 are provided for the purpose of securely clamping the fingers 48 and plate 46 in any desired position according to the size of the crucible to be used. The mechanism for positioning the gripping members relative to the top 47 of the crucible 10 is described in my above mentioned copending application.

In order that the crucible 10 after its removal from a furnace may be tilted to pour molten metal therefrom, it is desirable to connect the supporting unit 11 for turning movement relative to the supporting structure 12. To this end,

a trunnion 54 is preferably formed integral with each pair of vertical members 16. The trunnions 54 are provided with circumferential grooves 55 which provide circular trackways for the lower looped ends of substantially U-shaped members 56 connecting the crucible supporting unit 11 to the supporting structure 12 in a manner to be described.

The supporting structure 12 comprises a horizontal member 58 provided with an eye 59 which may be connected to a hook 60 of any suitable lifting apparatus. The members 56 are formed from metal rods which are doubled back on themselves and are suspended from the horizontal member 58 by nuts 61. Lock nuts 62 are provided to prevent upward movement of the members 56 relative to the horizontal member 58. By doubling the rods 56 back on each other, the ends of each rod, which are connected to the horizontal member 58, are parallel to and spaced from each other and the mid-portions 63 are formed in the shape of a semi-circle for sliding engagement with the groove 55. Spacing members 65 are connected between the parallel portions of each of the members 56 immediately above the trunnions 54 to prevent any spreading motion of the parallel portions of the members 56 adjacent the trunnions 54 which would permit disengagement of the semi-circular portions of the members 56 from the circular grooves 55.

It will be seen that the above described arrangement provides a pivotal support in the nature of a trunnion for the crucible supporting unit 11. However, it is desirable that the crucible supporting unit 11 may be rotated relative to the supporting structure 12 with a minimum of effort and, accordingly, the horizontal axis 66 of the trunnions 54 about which the turning movement takes place is preferably located adjacent the center of gravity of the supporting unit 11 and the crucible 10 supported thereby. Moreover, it is desirable that the unit 11 and the crucible 10 normally occupy a vertical position relative to the supporting structure 12 and, accordingly, the horizontal axis 66 is preferably located slightly above the center of gravity of the unit 11 and the crucible 10 supported thereby.

A handle 67 is provided to enable an operator to tilt the crucible for the purpose of pouring molten metal therefrom. The handle 67 has a cylindrical opening 68 formed in one end thereof for engagement with a member 69 projecting from the vertical member 13 of the supporting unit 11. The member 69 is secured to the vertical member 13 by any suitable means such as the rivets 70.

A collar 71 is formed on the end of the handle 67 and is engageable with a detent 72 to prevent disengagement of the lever 67 from the member 69 during that time in which the crucible 10 is tilted to pour metal therefrom. The detent 72 is pivotally connected to the vertical member 13 by a pivot pin 73 and is provided with a counterweight 74 which will maintain the point 72' of the detent 72 in constant engagement with the handle 67. Any disengaging movement of the lever 67 from its support 68 will operate to jamb the collar 71 against the point 72' of the detent 72, and to remove the lever 67 it will first be necessary to raise the counterweight 74 and thereby allow the collar 71 to clear the point 72' on the detent 72. It will be apparent that this arrangement will securely prevent disengagement of the lever 67 from the member 69.

During the removal of the crucible 10 from

a furnace, it is desirable to provide means for retaining the unit 11 in a substantially vertical position relative to the supporting structure 12. To this end, an abutment 15 is preferably formed 5 integral with the horizontal member 58 for the purpose of preventing turning movement of the unit 11 to the right, as viewed in Figure 4, at all times. A gravity actuated pawl 76 is also connected to the horizontal member 58 for normally 10 preventing turning movement of the unit 11 in the opposite direction. The pawl 76 is mounted on the horizontal member 58 by a plate 77 which permits sliding movement of the pawl 76 relative to the horizontal member 58. A handle 78 is 15 provided to enable an operator to raise the pawl 76 to permit turning movement of the unit 11 to the left, as viewed in Figure 4. The plate 77 is provided with a slot 79 through which the handle 78 protrudes whereby manual actuation of the 20 pawl 76 will be permitted.

In order that the unit 11 may be returned to its normal vertical position and locked in such position without the necessity of actuating the pawl or latch 76, the upper surface 80 of the 25 member 13 is inclined to provide a cam surface as shown in Figure 4. The bottom edge 81 of the pawl 76 has a similar inclination or is rounded to secure a camming action which will cause the pawl 76 to automatically ride up the surface 80 30 upon return of the unit 11 to its normal vertical position. It will be apparent that the latch 76 will drop to lock the unit 11 in its normal vertical position as soon as such position is reached.

The operation of the apparatus is as follows: 35 The plate 46 is adjusted in order that the gripping members 21 will be properly positioned relative to the sides of the crucible. When the parts of the apparatus are in normal position, the latch 76 will be operative to prevent turning 40 movement of the crucible supporting unit 11 relative to the supporting structure 12.

The mechanism may be lowered by the hook 60 until the plate 46 contacts the upper edge 47 of the crucible 10. The mechanism will then be in 45 a position for the gripping members 21 to properly engage the sides of the crucible 10. This is accomplished by applying a wrench to either end 31 of the shaft 23 and rotating this shaft to cause movement of the trunnions 36 away from each 50 other. Such movement of the trunnions 36 will impart a similar movement to the cradles 33 on the respective upper ends of the pivotally mounted members 18 whereby the crucible gripping members 21 on the respective lower ends of the 55 members 18 will be moved into engagement with the crucible 10. In such position the apparatus is operable to furnish a support by which the crucible can be transported.

When it is desired to tilt the crucible for the 60 purpose of pouring molten metal therefrom, the operator will slip the open end 68 of the handle 67 downwardly over the projecting member 69 secured to the supporting unit 11. It will be apparent that prior to such application of the handle 67 to the member 69, the point 72' on the 65 detent 72 will have been in engagement with the member 69. Upon downward movement of the handle 67 relative to the member 69, the collar 71 will contact the detent 72 and cam the same 70 out of engagement with the member 69. As soon as the collar 71 passes the point 72' on the detent 72, the counterweight 74 will cause a pivotal 75 movement of the detent 72 into engagement with the handle 67 at a point above the collar 71. In this position, it will be apparent that the detent 72 will be operable to prevent accidental disengagement of the lever 57 from the member 69.

Before a turning or tilting movement can be imparted to the crucible supporting unit 11 relative to the supporting structure 12, it will be 5 necessary for the operator to raise the handle 78 and latch 76. After releasing the latch 76 from engagement with the crucible supporting unit 11, the latter and the crucible supported thereby may be rotated to a position such as that shown in 10 dotted lines in Figure 4 for the purpose of pouring molten metal.

It obviously is desirable that the operator exert a force at right angles to the handle 67 to tilt the crucible, and if this operation is carefully 15 performed, there is no danger that the handle will become detached. Carelessness in handling an apparatus of this character is frequent, however, and in order to prevent injury to an operator or other nearby workman, the present construction provides means for positively preventing accidental detachment of the handle 67 from the projection 69. Regardless of any endwise pull on the handle 69, the engagement of the flange 71 with the detent 72 will positively prevent detachment of the handle, and accordingly the crucible cannot swing back to its normal position except under the control of the operator. Thus the apparatus provides means for preventing serious 20 and painful injuries to operators. Such mechanism forms the subject matter of my copending application Serial No. 246,236 referred to above. 30

After a pouring operation has been completed, the operator may reduce the pull on the handle 67 to permit the parts to swing back to their 35 normal position. As such position is approached, the cam face 80 will engage and lift the latch 76, and when the vertical member 13 reaches its normal position, the latch 76 will drop to operative position and the entire crucible supporting 40 unit 11 will be prevented from swinging. The handle may be readily detached, when desired, by manually lifting the counterweight 74 to move the detent 72 away from the flange 71, whereupon the handle may be moved endwise to disconnect it from the projection 69.

Attention is invited to the fact that the supporting unit 11, the levers 18 and their crucible engaging jaws, and the shaft 23 form a bodily 50 movable structure adapted to turn on the axis of the trunnions 54. The connection of the upper ends of the levers 18 to the shaft 23 and the journaling of the shaft 23 in the upstanding member 13 as well as the fixing of the shaft 23 against axial movement by the collars 25, and 55 the arrangement of the levers 18 between the pair of elements of each depending arm structure 16 effectively ties the various elements of the bodily movable structure together, thus preventing any relative movement of these parts, as is highly 60 desirable in the pouring of metal from relatively heavy crucibles. Moreover, the effective anchoring of the elements together renders it wholly practicable to employ the single latching element 76 to prevent bodily movement of the rocking 65 structure until the operator is ready to pour metal from the crucible. Accordingly the parts are effectively fixed against relative movement, except for the operation of the shaft 23 to move the jaws 21 during the lowering of the mechanism into the furnace, during the lifting of the crucible from the furnace and the transporting of the crucible to the point where the metal is to be poured. The upstanding member 13 is a relatively heavy rigid unit which carries both the U- 70 75

shaped structure comprising the elements 14 and 16 and the shaft 23, and it is necessary merely to project the upstanding member a sufficient distance upwardly to be engaged by the latch 76.

5 This latch, and the stop element 75 (Figure 4) both are carried by the transverse supporting arm 58. Thus this transverse arm is utilized to carry the eye 69 by means of which the mechanism is lifted to carry the depending supporting 10 rods 56, and to carry the latch 76 and stop element 75.

It will be apparent that the apparatus herein illustrated and described furnishes a convenient means for supporting a crucible. By having the 15 crucible supporting mechanism rotatably mounted with respect to a supporting structure, a convenient means for pouring molten metal from the crucible is provided. In addition, the locking mechanism is effective to prevent any uncontrolled movement of the crucible supporting 20 unit relative to the supporting structure.

It is to be understood that the form of the invention herewith shown and described is to be taken as a preferred example of the same 25 and that various changes in the shape, size and arrangement of parts may be resorted to without departing from the spirit of the invention or the scope of the subjoined claims.

I claim:

30 1. A device of the character described comprising a supporting unit, a mechanism carried thereby and movable into engagement with an article to be supported thereby, a supporting structure for said unit, said unit being connected 35 to said supporting structure for turning movement relative thereto whereby turning movement of the article relative to said supporting structure will be effected, said unit and said structure having interengaging portions normally pos- 40 sitively preventing turning movement of said unit in one direction from its normal position, and means for preventing relative turning movement of said unit in the other direction.

2. A device of the character described comprising a supporting unit, a plurality of crucible gripping members carried by said unit, mechanism for moving said members into engagement with the crucible to be supported thereby, a supporting structure for said unit, means connect- 45 ing said unit to said supporting structure for turning movement relative thereto whereby turning movement of the crucible relative to said supporting structure will be effected to permit pouring of molten metal from the crucible, said 50 unit and said structure having interengaging portions normally positively preventing turning movement of said unit in one direction from its normal position, and means for preventing relative turning movement of said unit in the other direction.

3. A device of the character described comprising an article supporting unit, a supporting structure for said unit, means connecting said unit to said structure for turning movement relative thereto, said unit and said structure having interengaging portions normally positively preventing turning movement of said unit in one direction from its normal position, and means for preventing relative turning movement of said 55 unit in the other direction.

4. A device of the character described comprising an article supporting unit, a supporting structure for said unit, means connecting said unit to said structure for turning movement relative thereto, said unit and said structure having 60

interengaging portions normally positively preventing turning movement of said unit in one direction from its normal position, and means for preventing relative turning movement of said unit in the other direction comprising latching mechanism interengageable with portions of said supporting unit and said supporting structure.

5. A device of the character described comprising a normally vertical article supporting unit engageable with an article to support it in a vertical position, a supporting structure for said unit, means connecting said unit to said structure for turning movement about a horizontal axis relative to said structure, said unit and said structure having interengaging portions normally positively preventing turning movement of said unit in one direction from its normal position, and locking mechanism for preventing movement of said supporting unit in the other direction from its normal vertical position, said locking mechanism being releasable to permit turning movement of said supporting unit.

6. A device of the character described comprising a normally vertical article supporting unit engageable with an article to support it in a vertical position, a supporting structure for said unit, means connecting said unit to said structure for turning movement about a horizontal axis relative to said structure, said horizontal axis passing adjacent the center of gravity of said supporting unit and the article supported thereby, and locking mechanism for preventing movement of said supporting unit in the other direction from its normal vertical position, said locking mechanism being releasable to permit turning movement of said supporting unit.

7. A device of the character described comprising a normally vertical article supporting unit engageable with an article to support it in a vertical position, a supporting structure for said unit, means connecting said unit to said structure for turning movement about a horizontal axis relative to said structure, means for positively preventing relative turning movement of said unit in one direction, and locking mechanism for preventing relative turning movement of said unit from its normal vertical position in the opposite direction, said locking mechanism being releasable to permit relative turning movement of said unit in said opposite direction.

8. A device of the character described comprising a normally vertical article supporting unit, a supporting structure for said unit, means connecting said unit to said structure for turning movement about a horizontal axis relative to said structure, a member rigid with respect to said supporting structure for preventing relative turning movement of said unit in one direction, and a gravity actuated pawl secured to said supporting structure and engageable with a portion of said unit for preventing relative turning movement thereof in the other direction from its normal vertical position.

9. A device of the character described comprising a supporting unit and a supporting structure, said unit comprising a substantially inverted U-shaped frame, an arm pivoted to the lower end of each arm of said frame, means for effecting relative movement of the lower ends of said pivoted arms toward and away from each other, and an article engaging member carried by the lower end of each pivoted arm, said supporting structure comprising a pair of substantially U-shaped supporting elements, trunnions 75

carried by the lower ends of the arms of said frame and rotatable in the looped lower ends of said supporting elements, and releasable latch means connected between said unit and said structure for preventing turning movement of the former on the axis of said trunnions.

10. A device of the character described comprising a mechanism having members movable into engagement with an article to be supported thereby, a supporting unit carrying said mechanism, a supporting structure, means for connecting said supporting unit to said supporting structure for turning movement on a horizontal axis, said unit having an upstanding member centrally thereof movable into proximity to the central portion of said supporting structure, and latch means cooperating between such central portion of said structure and said upstanding member for normally latching said unit against said turning movement.

11. A device of the character described comprising a supporting unit comprising a horizontal member, a pair of spaced depending arms and a central upstanding member, levers pivotally connected to said arms and having article engaging elements at their lower ends, means for operating said levers to bring said elements into engagement with an article, a supporting structure, means for pivotally connecting said unit to said supporting structure for turning movement on a horizontal axis, and means cooperating between said supporting structure and said upstanding member to normally prevent such turning movement.

35. 12. A device of the character described comprising a supporting unit comprising a horizontal member, a pair of spaced depending arms and a central upstanding member, levers pivotally connected to said arms and having article engaging elements at their lower ends, a screw shaft rotatably supported by said upstanding member and having threaded end portions connected to said levers to effect movement thereof to engage said elements with an article, a supporting structure, means for pivotally connecting said unit to said supporting structure for turning movement on a horizontal axis, and means cooperating between said supporting structure and said upstanding member to normally prevent such turning movement.

13. A device of the character described comprising a supporting unit comprising a horizontal member, a pair of spaced depending arms and a central upstanding member, levers pivotally connected to said arms and having article engaging elements at their lower ends, means for operating said levers to bring said elements into engagement with an article, a supporting structure of substantially inverted U-shape including a horizontal upper member and depending arms, means for pivotally connecting said unit to the lower end portions of said last named arms for turning movement on a horizontal axis, the upper end of said upstanding member, when in normal position, extending into proximity with the horizontal member of said supporting structure and engageable with a portion thereof to prevent turning movement of said unit in one direction, and a single latch means connected between the horizontal arm of said supporting structure and the upper end of said upstanding member to normally prevent turning movement of said unit in the other direction.

14. A device of the character described comprising a supporting unit comprising a horizontal member, a pair of spaced depending arms and a central upstanding member, levers pivotally connected to said arms and having article engaging elements at their lower ends, a screw shaft rotatably supported by said upstanding member and having threaded end portions connected to said levers to effect movement thereof to engage said elements with an article, a supporting structure of substantially inverted U-shape including a horizontal upper member and depending arms, means for pivotally connecting said unit to the lower end portions of said last named arms for turning movement on a horizontal axis, the upper end of said upstanding member, when in normal position, extending into proximity with the horizontal member of said supporting structure and engageable with a portion thereof to prevent turning movement of said unit in one direction, and a single latch means connected between the horizontal arm of said supporting structure and the upper end of said upstanding member to normally prevent turning movement of said unit in the other direction.

RAYMOND D. YORK. 50
